UNITED STATES PATENT OFFICE.

GUY O. SMITH, OF NEWTON, MASSACHUSETTS.

CAST-OFF FOR SUSPENDERS.

1,105,933.

Specification of Letters Patent. Patented Aug. 4, 1914.

Application filed January 21, 1909. Serial No. 473,506.

To all whom it may concern:

Be it known that I, GUY O. SMITH, of Newton, in the county of Middlesex and State of Massachusetts, have invented a new and useful Improvement in Cast-Offs for Suspenders, of which the following is a full, clear, and exact description, reference being had to the accompanying drawings, forming a part of this specification in explaining its nature.

The essential object of my invention is to provide a cast-off means or device by which the separate parts of the suspenders may be easily combined, securely held when combined, and cast off by a single act or operation as occasion may require.

My invention can best be seen and understood by reference to the drawings, in which—

20 Figure 1 shows in front elevation the means or device embodying my invention connecting parts of suspenders. Fig. 2 is a cross vertical section of said device. Fig. 3 shows in front elevation parts of said device to which special reference will herein-after be made. Fig. 4 shows in side elevation a portion of the device with suspender parts connecting therewith. Fig. 5 shows in cross vertical section a slightly modified 30 construction embodying my invention. Fig. 6 is also a vertical section showing the essential members of the modified device in a disengaging position. Fig. 7 shows in front elevation one of the essential members 35 of the modified form of device. Fig. 8 shows in cross vertical section a still further embodiment of my invention employing features of construction to which special reference will hereinafter be made.

40 Referring to the drawings:—1 represents the end portion of a suspender strap or web, the portion represented preferably indicating the end of one of the front straps or webs of suspenders.

45 2 represents the suspender ends, so called. I prefer to employ ends of the well known kind having double loops 3 and 4, respectively, one lying outside the other.

50 For connecting the suspender ends with the strap or webbing 1 of the suspenders there is provided the following described means or device. Connecting immediately with the strap or web 1 is a loop 5 having a crossbar 6. Making connection and preferably pivotal connection with this crossbar 55 is the base member 7 of a two part clasp.

This member is preferably struck up from a single blank and consists of a metal plate at the upper end of which there extends upwardly separate spaced arms 8, 8, which are turned around the crossbar 6 to make connection therewith as aforesaid. The member 7 depends from the crossbar hanging by these arms and at or near the bottom end of the body thereof there projects forward therefrom a curved tongue 9. Engaging also with the crossbar 6 is the cover member 10 of the above-mentioned clasp. This member is preferably struck up from a single blank and consists of a metal piece or plate made preferably slightly concave and which pivotally connects with the crossbar 6 by turning the end portion 11 of the member around said bar between the arms 8, 8, of the member 7. From the point of its connection with the crossbar the member 10 is extended so far that a portion 12 thereof, formed preferably by bending inwardly the end of said member, may yieldingly engage the under side of the curved tongue 9 of the 80 base member by slipping under and around this tongue, the two parts coöperating to form a separable fastener by which the two members are held together.

The members 7 and 10 are adapted to hold and retain between them a slide 14 arranged upon the loop or loops of the suspender ends and through which these loops are adapted to play. The slide 14 preferably comprises a metal shell or housing 90 made by bending up a flat metal blank of suitable length and edge configuration, which blank is bent from the point 15 at the center of its length and has sides separated to form an open space or cavity between 95 them, the ends of the piece being brought together. Within the cavity of the housing is contained an eyelet 16. This eyelet is centered within the housing by indenting one or both of its sides by an indentation 100 17 which extends into the hollow of the eyelet, the eyelet being then held securely in place by the bearing stress exerted by the sides of the housing. As said before, the slide 14 is arranged upon the portions 3 and 4 of the suspender ends, these portions extending loosely through the slide with the one portion 3 adapted to slide over the eyelet 16 as a bearing and the portion 4 over the interior of the turned end 15 of the 110 housing.

With reference now to the operation of

the device: The slide 14, arranged upon the loops of the suspender ends, is placed against the base member 7 with the end 15 of the housing resting upon the tongue 9 of this member. The cover is then turned down to engage the base member by the turned end 12 thereof clasping under its tongue 9. Thereupon the slide will become seated in the cavity formed between the respective members. For the purpose of centering and assisting in the retention of the slide in the cavity so provided, the base member may be upset by an indentation 18, which, when the slide is properly retained and seated as aforesaid, will enter the indentation 17 formed in the side of the slide. The slide will thus be retained as against lateral displacement, which mode of retention is also supplemented by the concavity 20 of the cover and also by flanges 19 extending from both sides of the slide which extend down on either side of the tongue. In further reference to the retention of the slide 14, it is to be noted that as the strain 25 of the parts causes the slide to draw against the tongue of the base member the strain will not come upon the tongue alone, but will come also upon the part 12 of the cover which reinforces the tongue at this point.

30 The slide may be released and drawn out from between the members for releasing the suspender ends by disengaging the cover from the base member when the slide will either fall away from the base member or be drawn away by the pull on the suspenders. The cover is disengaged from the base member by drawing upon a finger clip 20 projecting from the bent end 12 of the cover which engages the tongue as aforesaid. The 35 cover may also be disengaged and the slide pressed out of its socket by inserting the tip of the finger from the back of the base member through an opening 21 preferably formed in it. This opening 21 may be an opening 40 left by the striking up of the base member for forming the tongue 9.

In Figs. 5 to 8, inclusive, I have shown a slightly modified embodiment of my invention, the especial advantage of which resides 45 in the fact that the slide 14 is positively dislodged or drawn away from the base member upon opening the cover. As may be noted (especially with reference to Figs. 5 and 6), the end of the cover which is bent around 50 the crossbar 6 of the loop 5 forms not only a pivotal connection therewith, but is continued down by an extension or cast-out 22 between the arms 8 of the base member (see Fig. 7) so as to lie in back of the upper portion of the slide when seated. Accordingly 55 as the cover is turned away from the base member the part 22 will act to force the slide away from its bearing on the tongue 9, the cover carrying it until the slide is drawn away from the cover by the pull on the sus-

60 pender ends. In this modified construction, for seating the slide between the base member and cover, the slide is first applied to the cover by placing it upon the portion 12 of the cover and between the extension 22 and the main body of the cover, as may be seen by reference to Fig. 6. Upon then turning down the cover to engage the base member and as the portion 12 of the cover slips in beneath the tongue 9 of the base member, the tongue will slip in between the slide and the portion 12 of the cover when the slide will become properly seated as aforesaid. For assisting in centering and laterally retaining the slide when seated the cast-out is provided with an indentation 23 which fits within the indentation 17 in the side of the slide. Attention is also directed to the bar 24 formed in the base member against which the cast-out is adapted to bear when the members are connected. This for the purpose of preventing the cast-out from projecting back so far as to wear against the garments of one wearing the suspenders.

65 In Fig. 8 the cover is shown provided with a leather covering 25 which preferably extends over the cast-out 22, around the pivotal fastening of the cover and over its face to extend by a flap 26 beyond the end of the finger clip 20. Such a covering is oftentimes 70 desirable in cast-outs or fastenings for suspenders and provides also by the projecting flap portion 26 of the leather covering means which may be readily grasped by the wearer 75 of the suspenders for effecting a disengagement of its parts.

Having thus fully described my invention, I claim and desire to secure by Letters Patent of the United States:—

75 1. A cast-off for suspenders comprising 105 base and cover members pivotally connected whereby said cover may occupy an open or closed position with relation to said base member, each of said members being provided with parts coöperating with one another to form a releasable clasp for retaining said members when said cover is occupying a closed position and which clasp is broken by the opening of said cover, and a slide socketed to lie between said members and be retained thereby when said cover is closed and releasable therefrom upon the opening of said cover and breaking of said clasp as aforesaid.

80 2. A cast-off for suspenders comprising 110 base and cover members pivotally connected whereby said cover may occupy an open or closed position with relation to said base member, each of said members being provided with parts coöperating with one another to form a releasable clasp for retaining said members when said cover is occupying a closed position and which clasp is broken by the opening of said cover, and a slide socketed to lie between said members with bear- 115 120 125 130 135

ing against said clasp when said cover is occupying a closed position and which slide is releasable from said members upon the opening of said cover and the breaking of 5 said clasp as aforesaid.

3. A cast-off for suspenders comprising base and cover members pivotally connected whereby said cover may be turned to occupy an open or closed position with relation to 10 said base member, said base member having a projecting tongue and said cover being bent to coöperate with said tongue to form a clasp retaining said members when said cover is closed, said clasp being broken by 15 the opening of said cover, and a slide socketed to lie between said members and having bearing against said tongue when said cover is closed and releasable therefrom upon the opening of said cover and breaking of said 20 clasp as aforesaid.

4. A cast-off for suspenders comprising base and cover members pivotally connected whereby said cover may be turned to occupy an open or closed position with relation to 25 said base member, each of said members being provided with parts coöoperating with one another to form a releasable clasp for retaining said members when said cover is closed and which clasp is broken by the opening of said cover, and a slide comprising 30 a housing and eyelet contained therein socketed to lie between said members and having bearing against said clasp when said cover is closed and which slide is releasable upon the opening of said cover and breaking 35 of said clasp as aforesaid.

GUY O. SMITH.
